UNITED STATES PATENT OFFICE.

JOSEPH C. HASLAM, OF SAN FRANCISCO, CALIFORNIA.

GARTER.

1,367,778.

Specification of Letters Patent.

Patented Feb. 8, 1921.

Application filed August 3, 1920. Serial No. 401,063.

To all whom it may concern:

Be it known that I, JOSEPH C. HASLAM, a citizen of the United States, residing in the city and county of San Francisco and State of California, have invented a new and useful Improvement in Garters, of which the following is a specification.

My invention relates to improvements in garters wherein a bifurcated member, arranged to constrict, by winding, the upper portion of a stocking or sock to provide greater frictional contact between said stocking and the limb of a wearer, operates in conjunction with means for rotating the same and for preventing rotation thereof to retain said stocking in position.

The primary object of the present invention is to provide a new and improved garter.

20 A further object of the invention is to provide a new and improved garter having a greatly simplified construction whereby the same may be easily, quickly and efficiently operated, and economically produced.

A still further object of the present invention is to provide a new and improved garter arranged to wind the elastic or ribbed portion, usually found on the upper end or portion, of a stocking or sock for the purpose of constricting the same to provide greater frictional contact between the stocking and the limb of the wearer to hold said stocking firmly in position without the use 35 of elastics, cords, or other encircling media which might tend to bind and injure the said limb.

A still further object is to provide an improved garter arranged to extend the area 40 of pressure of a stocking or the like over the limb of a wearer whereby a sufficient area of contact may be provided to firmly hold the stocking in position without bringing undue or excessive pressure upon said limb.

I accomplish these and other objects by means of the improved device disclosed in the drawings forming a part of the present specification, wherein like characters of 50 reference are used to designate similar parts throughout the said specification and drawings, and in which:

Figure 1 is a broken elevation of a portion of a human limb and sock thereon dis-

closing my improvement applied thereto 55 and before constriction of said sock;

Fig. 2 is a similar view disclosing the manner in which the upper portion of the sock is constricted by rotation of the device;

Fig. 3 is an enlarged side elevation of the device in the unlocked position;

Fig. 4 is a vertical sectional view of the device in a locked position; and

Fig. 5 is an enlarged transverse sectional view taken on line 5—5 of Fig. 2 in the direction indicated.

Referring to the drawings the numeral 1 is used to designate a split or bifurcated member, preferably of resilient or flexible material, arranged to engage both sides or surfaces of the upper or ribbed portion 2 of a sock or stocking 3.

A spatular member 4 is pivotally connected to the upper portion of the bifurcated or split member 1 as at 5, whereby said member 1 may be rotated to wind the fabric of said upper portion upon the member 1 and thereby constrict the periphery of that portion of the stocking to provide 80 greater frictional contact of the sock or stocking 1 with the limb 6 of the wearer.

The operation is as follows:

The bifurcated or split member 1 is placed on the upper edge of the ribbed or elastic portion 2 of the sock 3 with the bifurcations thereof engaging both sides of the said elastic or ribbed portion 2, or, in other words, the upper edge of the elastic or ribbed portion 2 of the sock 3 is placed 90 within the split or slot of the split member 1, with the spatular member 4 extending longitudinally from its pivotal point 5 of the member 1 as disclosed in Fig. 1 of the drawings. By means of the spatular member 4 the split or bifurcated member 1 is rotated to wind a portion of the elastic or ribbed portion 2 thereon and thereby constrict the periphery of the upper edge of said sock to provide a greater frictional contact between said ribbed portion 2 and the leg 6 of the wearer and thereby retain 100 said sock in position.

By providing member 1 of sufficient length it is obvious that the pressure will be distributed over an annular path of considerable width and area, and while a greater pressure is obtained than in the present

method of pulling upwardly on the upper edge of the sock or stocking at one or more points, said pressure being distributed over a greater area provides a lesser pressure per 5 square inch.

Therefore, there can be no danger of providing or applying a pressure great enough to prevent proper circulation within the limb upon which the sock is worn. But it 10 should be noted that various degrees of pressure may be applied and that said pressure will be in direct proportion to the number of turns or revolutions made by the bifurcated or split member 1.

15 To prevent unwinding of the elastic portion, the spatular member 4 is rotated upon its pivot and positioned between the elastic portion of the sock and the limb of the wearer, as disclosed in dotted lines in Fig. 2 20 of the drawings.

This position is also disclosed in Fig. 5 of the drawings wherein it is apparent that the spatular member 4 is firmly held between the elastic portion 2 of the sock 3 and the 25 limb 6 of the wearer and while in this position is held against movement which will prevent rotation of the bifurcated member 1 in a direction which will unwind the sock therefrom.

30 It is obvious from the foregoing that I have provided an improved garter adapted to restrict the elastic or upper portion of a sock or stocking or the like to increase frictional contact between said sock and limb to 35 retain said sock or stocking in position.

It is also obvious that by distributing the pressure of said sock or stocking over a comparatively greater area of contact that a more firm contact may be obtained between 40 the sock and limb without excessive pressure.

It is further evident that by means of my improved garter a sock or stocking may be easily and readily held in position without the use of encircling cords, elastics or other 45 similar media.

Having thus described my invention what I claim as new and desire to secure by Letters Patent is:

1. A garter comprising a split member arranged to engage the upper edge of a stocking; and means pivotally mounted upon said split member and arranged to rotate the same to wind said upper edge upon said member to constrict the periphery, and thereby provide greater frictional engagement of said upper edge with the limb of a wearer to retain said stocking in position. 50

2. A garter comprising a split member arranged to engage the upper edge of a stocking; and means pivotally mounted upon said split member and arranged to rotate the same to wind said upper edge upon said member to constrict the periphery, and thereby provide greater frictional engagement of said upper edge with the limb of a wearer to retain said stocking in position, 55 said means being arranged to prevent unwinding of said member when said means are positioned between said stocking and said limb. 60

3. A garter comprising a bifurcated member arranged to engage the upper portion of a stocking on each side thereof; and means pivotally connected to said member for rotating the same to wind said upper portion 75 of the stocking thereon, whereby said portion may be constricted to provide greater frictional contact of said stocking with the limb of a wearer, said means being arranged to be positioned between said stocking and 80 the limb of the wearer to prevent unwinding of said stocking from said member. 70

4. A garter comprising a bifurcated spring member arranged to resiliently engage both sides of the upper portion of a stocking; and a spatular member pivotally connected to the bifurcated member whereby the same may be rotated to wind and constrict said upper portion to provide greater frictional contact with the limb of a wearer, said spatular member being arranged to be positioned 90 between the said stocking and limb to prevent unwinding of said stocking. 85

In witness whereof I hereunto set my signature.

JOSEPH C. HASLAM.
